(57) **CLAIM**

The ornamental design for a bullet, as shown and described.

DESCRIPTION

FIG. 1 is an isometric view of a bullet in accordance with the new design;

FIG. 2 is a right-side view thereof;

FIG. 3 is a front side view thereof;

FIG. 4 is a left side view thereof;

FIG. 5 is a back-side view thereof;

FIG. 6 is a top side view thereof;

FIG. 7 is a bottom side view thereof;

FIG. 8 is an isometric view of the front part of the bullet
entering into a firearm rifled barrel;

FIG. 9 is a cross-sectional view of the front part of the bullet
inside the rifled barrel;

FIG. 10 is an isometric view of the bullet with the single
driving ban of the bullet inside the rifled barrel;

FIG. 11 is a cross-sectional view of the driving band of the
bullet inside the rifled barrel;

FIG. 12 is an isometric view of the entire bullet inside the
rifled barrel; and,

FIG. 13 is a cross sectional view of the rear part of the bullet
inside the rifled barrel.

The broken lines shown in the drawings form no part of the
claimed design.

1 Claim, 7 Drawing Sheets
